STEREOSCOPIC PROJECTOR

Lee R. Wottring, Altadena, Calif.

Application August 8, 1949, Serial No. 4,349

Term of patent 14 years

(Cl. D61—1)

To all whom it may concern:

Be it known that I, Lee R. Wottring, a citizen of the United States, residing at Altadena, in the county of Los Angeles and State of California, have invented a new, original, and ornamental Design for Stereoscopic Projector, of which the following is a specification, reference being had to the accompanying drawing, forming part thereof.

Fig. 1 is a front perspective view of a stereoscopic projector, showing my new design; and

Fig. 2 is an elevational view of the opposite side thereof.

The essential features of my design reside in the parts shown in full lines.

I claim:

The ornamental design for a stereoscopic projector, as shown and described.

LEE R. WOTTRING.
